UNITED STATES PATENT OFFICE.

JOSIAH SULLIVAN AND CHARLES E. SULLIVAN, OF McCOOK, NEBRASKA.

TRAIN-PIPE COUPLING.

980,135.

Specification of Letters Patent. Patented Dec. 27, 1910.

Application filed July 23, 1910. Serial No. 573,405.

To all whom it may concern:

Be it known that we, JOSIAH SULLIVAN and CHARLES E. SULLIVAN, citizens of the United States, residing at McCook, in the 5 county of Redwillow, State of Nebraska, have invented a new and useful Train-Pipe Coupler, of which the following is a specification.

It is the object of this invention to provide, in a simple, merchantable and inexpensive form, a coupling device for train pipes, so constructed that when the cars are brought together, the coupling of the train pipes will be automatically effected.

15 Another object of the invention is to provide a coupling device of the sort hereinbefore mentioned, so constructed that when cars are brought together, a continuous passage through the train pipes will be secured, 20 this continuous passage being broken as soon as the cars are separated.

Another object of the invention is to provide a coupling for train pipes, so devised that the coupling upon one car will at all 25 times be axially alined to impinge upon another similar coupling, the couplings, however, being so mounted that a continuous train pipe passage may be maintained even when the cars are rounding a curve of extremely small radius.

30 The drawings show typical embodiments merely, and it is to be understood that changes, properly falling within the scope of what is claimed, may be made without departing from the spirit of the invention.

In the drawings,—Figure 1 shows the invention in side elevation; Fig. 2 is a longitudinal section of one of the coupling elements; Fig. 3 is a side elevation of one of 40 the coupling elements; Fig. 4 is a vertical transverse section upon the line A—B of Fig. 1; and Fig. 5 is a fragmental horizontal section of the tubular coupling member.

In the drawings, the car body is denoted 45 generally by the numeral 1. Secured to the lower face of the car body, are spaced beams 2, disposed longitudinally of the car body. These beams 2 are connected by an angle plate, hereinafter referred to as the support, 50 the horizontal flange 3 of the angle plate being bolted or otherwise secured to the beams 2, the other flange 4 of the angle plate depending in vertical position beneath the car. This angle plate, together with the beams

2, serves to define a channel in which the 55 coupling beam 5 may be slidably mounted.

The invention further includes a tubular coupling member, denoted by the numeral 6. This tubular coupling member 6 comprises a portion 7 and a portion 8, the portion 8 being slightly larger in diameter than the portion 7. The portion 7 is inserted through a suitable opening in the vertical flange 4 of the angle plate, this opening in the vertical flange being of sufficient size so 60 that the reduced portion 7 of the coupling member may have a swiveled movement therein.

The difference in diameter between the portions 7 and 8 of the tubular coupling member, results in the formation of a shoulder 9 upon the outside of the said coupling member, and in the formation of a shoulder 10 upon the inside of the said coupling member. The shoulder 9 is adapted to bear 75 against the rear face of the vertical flange 4 of the angle plate.

Secured to the forward end of the tubular coupling member is a head, the same comprising an outstanding flange 11 and a resilient disk 12, resting against the flange. The disk 12 is surrounded by a band 14, and is dished, as shown at 15, upon its forward face. The portion 7 of the tubular coupling member is extended through the disk 12, and through a plate 16, bearing against the forward face of the disk 12, the forward end of the portion 7 of the tubular coupling member being butt ended, as at 17, or otherwise 85 equipped, to hold the disk 12 firmly against 90 the flange 11. The portion 7 of the tubular coupling member is surrounded by a compression spring 18, the forward end of which bears against the flange 11, the rear end of the compression spring 18 bearing against the washer 19, surrounding the portion 7 of the coupling member, the washer 19 bearing 95 against the forward face of the vertical flange 4 of the angle plate.

At this point it may be stated that the spring 18, bearing against the head formed by the members 11 and 12, serves to hold the shoulder 9 against the rear face of the vertical flange of the angle plate, and since this shoulder 9 is disposed in a plane substantially normal to the axis of the tubular coupling member, the coupling member will be held yieldingly in 100 position to engage with a similar coupling 105

member upon another car, as shown in Fig. 1, when two cars are brought together. Moreover, by reason of the fact that the portion 7 of the tubular coupling member is mounted for swivel movement in the vertical flange 4 of the angle plate, the contact between the disk 12 of one car and the corresponding disk of another car, will not be broken when the train rounds a curve.

10 Disposed transversely in the portion 7 of the tubular coupling members, are spaced guides 20 in which a valve stem is mounted for sliding movement. This valve stem consists of a rod 21, the forward end of which 15 protrudes beyond the discharge end of the coupling member, the protruding end of the rod 21 being provided with a suitable head 22, adapted to impinge the like head upon another car. The rear end of the rod 21 20 carries a piston 23, adapted to reciprocate in the portion 8 of the tubular coupling member. A spring 24 is located within the portion 8 of the tubular coupling member, this spring 24, at its forward end, bearing against 25 the piston 23, to hold the same yieldingly in contact with the shoulder 10 formed upon the inside of the coupling member by the difference in diameter between the parts 7 and 8. The rear end of the spring 24 abuts 30 against the cap 25, threaded or otherwise secured, removably, to the rear end of the portion 8. By removing this cap 25, access may be had to the interior of the part 8 of the coupling member, for the purpose of repairing and for cleaning the device. The portion 35 8 of the coupling member is provided with an inlet port 26, this inlet port 26 being positioned between the shoulder 10 and the cap 25, the inlet port 26 communicating with 40 the train pipe 27.

By referring to Fig. 2 it will be seen that the spring 24 acts to hold the piston 23 against the shoulder 10, and between the inlet port 26 and the discharge end of the coupling member. Thus, when the cars are uncoupled, air cannot pass through the tubular coupling member. When, however, the cars are brought together, as shown in Fig. 1, the head 22 upon one car will engage with 45 the head 22 upon a similar car, causing the rods 21 to slide rearwardly, and disposing the pistons 23 between the inlet ports 26 and the caps 25. By this operation, a continuous train pipe connection will be effected 50 through all of the cars which are coupled together. However, should one or more cars be detached from the train, the spring 24 will act promptly to dispose the piston 23 in the position shown in Fig. 2, thereby preventing the egress of air from the tubular coupling member.

It is to be noted that the difference in diameter between the parts 7 and 8, results in the formation of the shoulders 9 and 10, the shoulder 9 being effective to maintain the axis of the tubular coupling member in proper relation for coupling, and the shoulder 10 serving as an abutment for the piston 23. A train equipped with the train pipe coupling mechanism herein disclosed, may 65 be uncoupled and coupled together at will, the train pipe connection being automatically continued from car to car, as the coupling operation is effected.

Having thus described the invention what 70 is claimed is:—

1. In a device of the class described, a support; a tubular coupling member slidable in the support and provided with an inlet port; a valve having a stem protruding at 80 one end beyond the discharge end of the coupling member; means for yieldingly holding the valve between the port and the discharge end of the coupling member, the coupling member being enlarged in diameter 85 intermediate its ends, to define in the interior thereof a shoulder to receive the valve, and to define upon the exterior of the coupling member a shoulder to bear against the support; and resilient means for normally holding the said shoulder in contact with the support.

2. In a device of the class described, a car body; spaced beams extended longitudinally of the car body; an angle plate having one of its flanges connecting the beams to define with the beams a channel for the reception of a coupling beam, the other flange of the angle plate being disposed in upright position beneath the car body; a 100 tubular coupling member swiveled in the upright flange of the angle plate; a head secured to the forward end of the coupling member; resilient means for actuating the head away from the upright flange of the 105 angle plate; and means engaging the upright flange of the angle plate to maintain the axis of the coupling member normally at right angles thereto.

In testimony that we claim the foregoing 110 as our own, we have hereto affixed our signatures in the presence of two witnesses.
